FLOAT CONTROLLED VALVE

Filed June 20, 1929

FIG. 1.

FIG. 2.

FIG. 4.

INVENTOR.

Douglas Kent Warner,
Geo. P. Kimmel
ATTORNEY.

UNITED STATES PATENT OFFICE

DOUGLAS KENT WARNER, OF BRISTOL, CONNECTICUT

FLOAT-CONTROLLED VALVE

Application filed June 20, 1929. Serial No. 372,482.

This invention relates to a float controlled valve and has for its primary object to provide, in a manner as hereinafter set forth, a valve of such class in which the float is balanced in a manner to provide for the utilization of substantially the full buoyancy of the displaced liquid to operate the valve without the expenditure of any appreciable proportion of such buoyancy to merely lift the float.

A further object of the invention is to provide a valve of the type aforesaid in which the float may be constructed of any suitable material without regard to the ratio between the specific gravity of such material and that of the liquid with which the valve is to be used.

A further object of the invention is to provide a valve of the class aforesaid which is invertible in order that the same may be selectively adapted for use as a low pressure type valve or as a high pressure type valve.

With the foregoing and other objects in view, the invention consists of the novel construction, combination and arrangement of parts as hereinafter more particularly described, and as illustrated in the accompanying drawings wherein is shown an embodiment of the invention, but it is to be understood that the description and drawings are to be taken as illustrative and that the invention is intended to be limited only by the scope of the claims hereunto appended.

In the accompanying drawings in which like numerals are employed to designate like parts throughout the same:

Figure 1 is a vertical section through a valve in accordance with this invention showing the same in position for use as a high pressure type valve and in association with a float chamber casing.

Figure 2 is a view similar to Figure 1 showing the valve in position for use as a low pressure type valve.

Figure 3 is a top plan of the valve as shown in Figure 1.

Figure 4 is a section taken on line 4-4 of Figure 1.

Referring to the drawings in detail, the numeral 1 indicates a casing, the interior of

which constitutes a float chamber 2, and which is formed with a plurality of openings 3 having threaded walls in order that communication may be established between the chamber 2 and any external apparatus with which it is desired to use the valve. One end of the casing is open and is adapted to be closed by means of a valve head 4 which may be secured by suitable holdfast devices 5 to a flange 6 formed on the casing adjacent the open end thereof.

Extending through the valve head 4 is an opening 7 which is formed adjacent its inner end with a neck 8. Communicating with the opening 7 is an auxiliary opening 9 which extends through the valve head 4 and which may be regulated by means of a manually operable valve stem 10. This opening permits bypassing valve if out of order and of increasing its capacity by a fixed opening. Formed on the inner face of the valve head 4 is a shank 11 which extends into the casing 1 and to which is pivotally connected a float designated generally by the numeral 12. The float 12 consists of a hollow body portion 13 upon one end of which is formed a counterbalance 14. The counterbalance 14 is of solid construction and is provided with a recess 15 into which the shank 11 extends. The float is pivotally supported on the shank 11 by means of a pivot pin 16 which extends through the shank adjacent the free end thereof and through the side walls of the recess 15.

Disposed within the recess 15 is a needle 17 which is pivotally supported on a pin 18 extending through the needle adjacent one end thereof and through the side walls of the recess 15. The float 12 is preferably balanced so that its center of gravity is slightly to the rear of the vertical plane of the pivot 16 when the casing 1 is disposed horizontally. With the casing thus disposed and with the valve head arranged as shown in Figure 1, the outer end of the needle 17 will be brought into engagement with the outer wall of the neck 8 whereby the neck is closed until a lifting force is exerted on the body portion 13 of the float by a liquid which may

be introduced into the chamber 2. When the valve head is inverted as shown in Figure 2, the needle 17 will be normally held out of contact with the wall of the neck 8 whereby the neck remains open until a lifting force is exerted on the body portion 13 of the float to force the outer end of the needle 17 into engagement with the rear wall of the neck 8.

It is thought that the many advantages of a valve in accordance with this invention will be readily apparent, and although the preferred embodiment of the invention is as illustrated and described, it is to be understood that various changes in the size, shape and arrangement of parts may be resorted to, so long as such changes fall within the scope of the invention as defined in the appended claims.

What I claim is:

20 1. In a valve structure, a float including a hollow body portion and further including a counterbalance formed on one end of the body portion, said counterbalance being formed with means for pivotally connecting the float with a support, and a port closing element pivotally connected to said counterbalance and extending longitudinally of the float.

2. In a valve structure, a float including a hollow body portion and further including a counterbalance formed on one end of the body portion, said counterbalance being formed with means for pivotally connecting the float with a support, and a needle pivotally connected to said counterbalance and extending longitudinally of the float.

3. In a valve structure, a valve head having a shank formed on its inner face, a float including a hollow body portion and further including a counterbalance formed on the forward end of the body portion, said counterbalance being provided with a recess into which said shank extends, means for pivotally connecting said shank with the side walls of said recess, and a needle pivotally connected to the side walls of said recess and extending longitudinally of the float.

4. In a valve structure, a valve head having a shank formed on its inner face, a float including a hollow body portion and further including a counterbalance formed on the forward end of the body portion, said counterbalance being provided with a recess into which said shank extends, means for pivotally connecting said shank with the side walls of said recess, and a needle pivotally connected to the side walls of said recess and extending longitudinally of the float, said float having its center of gravity rearwardly of the vertical plane of the pivotal connection between the counterbalance and shank.

5. In a valve structure, a valve head having an opening extending therethrough and further having a shank projecting from the

inner face thereof, a float including a hollow body portion and further including a counterbalance formed on the inner end of the body portion, said counterbalance being provided with a recess into which said shank extends, means for pivotally connecting the counterbalance to said shank, and a needle pivotally connected to the float and extending longitudinally thereof for engagement with the opening through the valve head.

6. In a valve structure, a casing formed with an open end, a valve head for closing said open end, said valve head having an opening extending therethrough and further having a shank projecting from the inner face thereof, a float including a hollow body portion and further including a counterbalance formed on the forward end of the body portion, said counterbalance being provided with a recess into which said shank extends, means for pivotally connecting the counterbalance and shank, and a needle pivotally connected to the counterbalance and extending longitudinally of the float for engagement with the opening through the valve head.

7. In a valve structure, a casing formed with an open end, a valve head for closing said open end, said valve head having an opening extending therethrough and further having a shank projecting from the inner face thereof, a float including a hollow body portion and further including a counterbalance formed on the forward end of the body portion, said counterbalance being provided with a recess into which said shank extends, means for pivotally connecting the counterbalance and shank, and a needle pivotally connected to the counterbalance and extending longitudinally of the float for engagement with the opening through the valve head, said valve head being invertible with respect to said casing.

8. In a valve structure, a casing formed with an open end, a valve head for closing said open end, said valve head having an opening extending therethrough and further having a shank projecting from the inner face thereof, a float including a hollow body portion and further including a counterbalance formed on the forward end of the body portion, said counterbalance being provided with a recess into which said shank extends, means for pivotally connecting the counterbalance and shank, and a needle pivotally connected to the counterbalance and extending longitudinally of the float for engagement with the opening through the valve head, said valve head having a manually closable, auxiliary opening extending therethrough.

9. In a valve structure, a valve head having a shank formed on its inner face, a float including a hollow body portion and further including a counterbalance formed on the

forward end of the body portion, said counterbalance being provided with a recess into which said shank extends, means for pivotally connecting said shank with the side walls of said recess, and a port closing element connected to said counterbalance.

5 In testimony whereof, I affix my signature hereto.

DOUGLAS KENT WARNER.
